UNITED STATES PATENT OFFICE.

JOSEPH KRABEC, OF CHICAGO, ILLINOIS.

DRIVING MECHANISM FOR WASHING-MACHINES.

1,357,999.

Specification of Letters Patent.

Patented Nov. 9, 1920.

Application filed December 5, 1919. Serial No. 342,750.

To all whom it may concern:

Be it known that I, JOSEPH KRABEC, a citizen of the United States, residing at Chicago, in the county of Cook and State 5 of Illinois, have invented a certain new and useful Improvement in Driving Mechanism for Washing-Machines, of which the following is a specification.

My invention relates to driving mechanisms for washing machines, more particularly of the type wherein the washing element is reversible. In the design illustrated, I have shown a machine having a cylinder which rotates several times in one direction and then reverses its movement and rotates an equal number of times in the opposite direction. The general object of the invention is to provide safe, simple and sure acting means for effecting such rotation in the rotary washing element. Contributory to the general object, it is my purpose to provide an advantageous form of mechanical movement in which a star wheel or Geneva gear is employed in association 15 with full stroke mechanism for insuring a full shift of the reversing clutch. Another object is to provide a star wheel having crowned points whereby it will be rotated slightly backward or forward in case it is not in proper position for its driving pin to enter one of its slots. Another object 20 is to provide means whereby the machine may at any time be instantly thrown into neutral position, to stop it without waiting 25 to stop the motor. Another object is to provide a construction in which the operating parts or mechanical movement are mounted beneath the main receptacle and are practically inclosed within a housing. Another 30 object is to provide means for yieldingly locking the star wheel in position to receive the driving pin.

I attain my objects by the mechanism illustrated in the accompanying drawings, 45 in which,

Figure 1 is an end elevation of a washing machine embodying my invention.

Fig. 2 is a side elevation thereof.

Fig. 3 is a sectional elevation on the irregular line 3—3, Fig. 4.

Fig. 4 is a top plan view of the parts shown in Fig. 3.

Fig. 5 is a view partly diagrammatic in its character showing the rock shaft which 55 controls the clutch and the mechanism

which controls the rock shaft. This view is diagrammatic in the sense that the parts are not shown in their actual positions but rather in a manner to illustrate their cooperative relationship, the rock shaft being 60 foreshortened for the purpose.

Fig. 6 is a sectional detail looking toward the left, Fig. 4, upon a plane indicated approximately by the line 6—6, Fig. 4. This view also shows the emergency clutch shifter by which the clutch may be instantly thrown to neutral position and the machine stopped.

Fig. 7 is a sectional detail showing the star wheel and associated parts and illustrating more particularly the yieldable lock by which the wheel is held in position to receive the actuating pin.

Like numerals denote like parts throughout the several views.

In the form selected to illustrate the invention, the washing machine has a tub or receptacle 1 which is U-shaped and supported upon a frame 2. A cylinder 3 is journaled within the receptacle so as to rotate about a horizontal axis. One of the gudgeons 4—4, by which the cylinder is supported, is provided with a sprocket wheel 5 for driving it. The sprocket is driven by a chain 6 driven from another sprocket 7 located in the present case in a housing 8 carried by the main frame beneath the receptacle 1. Sprocket 7 is rigidly secured to a jack shaft 10 journaled in stationary bearings 11 best shown in Fig. 4. Rigidly fastened to said jack shaft is a bevel gear wheel 12 which forms part of the transmission. The main power shaft 15 is arranged at right angles to the axis of bevel gear 12 and is journaled in stationary bearings 16, 16. Said shaft is driven by any suitable power device, for example, a motor 18 having a worm 19 meshing with a worm gear 20 fastened on the shaft. Loosely mounted on shaft 15 are two bevel gears 22, 23. These are rotatable independently of the shaft and of each other but are fixed against movement in an axial direction.

They are both permanently in mesh with the bevel gear 12. Located between the gears 22 and 23 on shaft 15 is a clutch 25 which is slidable and is adapted to engage their hubs 24, 26 alternately. The shaft has a spline 27 which permits the clutch to slide but compels it to rotate in unison 110

with the shaft. Hubs 24, 26 are far enough apart to permit the clutch to occupy a neutral position out of engagement with either of them. When the clutch is shifted to either one of its extreme positions it will drive the engaged bevel gear and rotate the bevel gear 12 in one direction or the other in the manner well known in connection with reversible transmissions.

10 Clutch 25 is shifted by means of a fork 30 fastened to a slide rod 31 mounted in stationary bearings 32. Said rod is subject to the actions of two mechanisms—one the emergency throwout, and the other the reversing mechanism which acts under normal running conditions to rotate the cylinder first one way and then the other. I will first describe the emergency mechanism, which includes a V-shaped block 35 rigidly fastened to one end of the slide rod 31, as best shown at the left end of Fig. 4. The acting faces of this block form cams adapted to coöperate with a neutralizing bar 38, one end of which is slidably supported in a stationary bracket 39. The parts are so formed that when bar 38 is pushed toward the block, it will shift the latter to neutral position and lock it there thus causing the slide rod 31 to bring the clutch 25 to neutral, 30 non-acting position to stop the machine. Bar 38 is actuated by an arm 41 rigidly fastened to a rock shaft 42 as best shown in Fig. 6 and the left lower corner of Fig. 4. This rock shaft is journaled in a stationary bearing 45 and operated by an emergency lever 46 located outside the machine as shown at the lower left corner of Fig. 1. This lever is within easy reach of the operator at all times, and by rotating it, the operator can instantly bring the machine to a standstill.

Now referring to the automatic means for controlling the slide rod 31, block 35 is pivotally connected to the free end of a rocker arm 50 rigidly fastened to a rock shaft 51. This shaft is journaled in stationary bearing 52, 52 and has a rocker arm 55 rigidly fastened to it. The free end of arm 55 is longitudinally slotted to receive a pin 56 extending from the side of a reversing arm 57. This arm is loosely mounted upon a shouldered screw pin 60 screwing into a stationary bracket 61 as shown in sectional detail in Fig. 7. In the best construction this reversing arm extends in both directions from its supporting pin or pivot. A star wheel 63 is also mounted on pin 60 at the side of arm 57 and it also is loosely mounted. The result is that arm 57 and wheel 63 are rotatable independently 50 of each other, but are held against movement in an axial direction. Wheel 63 has a pin 64 extending from its side in position to engage arm 57 at a point on the opposite side of the pivot from pin 56.

65 Said wheel 63 has certain of the charac-

teristics of the well known Geneva gear for producing intermittent rotary movement. It has a number of radial slots 67 in its periphery for the reception of a driving pin 69 extending from the side of an arm 70 rigidly fastened to the back of the bevel gear 12. The result is that as arm 70 rotates about shaft 10 in unison with bevel gear 12, the pin 69 will enter one slot after the other, each time imparting a partial rotary movement to the star wheel. It will be understood, of course, that the number of slots in the wheel may be varied to correspond to the number of times it is desired to have the cylinder rotate before reversing.

75

In order to prevent the machine from wrecking itself in case the star wheel should be rotated when the pin 69 is out of engagement with it, the points of the star wheel are crowned in the manner illustrated in Figs. 3 and 5, the result being that if the star wheel is not accurately positioned to receive the pin, the pin upon approaching it will strike one side or the other of the peak of a crown and rotate the wheel backward or forward sufficiently to enable the pin to enter a slot.

80

The star wheel is provided with means for yieldingly holding it in the position in which it is left by the pin 69, thus presenting the next slot in position to be entered by the pin 69 as it approaches the wheel on its next revolution. These locking means consist of a ball catch as shown in Fig. 5 and in section in Fig. 7. On the side of the wheel are shallow pockets 75 arranged in a circle concentric with the wheel, one for every slot in it. A ball 76 is mounted in a chamber formed in the bracket 61 and is backed up by a helical compression spring 77. This spring is backed up by a screw plug 78. If pressure is exerted on the wheel, to rotate it, the ball will be pushed back, and the wheel may be rotated, but otherwise will hold its position.

95

100 Means are also provided for insuring a full stroke or shifting movement of the clutch 25. Secured to the rock shaft 51 is an arm 80 carrying an antifriction roller 81 at its free end. This is adapted to be engaged by a yieldable latching element here shown in the form of a plunger 83 having a wedge shaped nose. The plunger is slidably mounted in a stationary cylinder 84 shown in section in Fig. 5. A screw plug 85 screws into the rear end of said cylinder 105 and backs up a helical compression spring 86 which in turn backs up the plunger. The result is that the nose of the plunger always tends to throw the arm 80 completely to one side or the other and thereby produce a full movement of the clutch to one acting position or the other.

115

120 Operation: Under normal operating conditions, the emergency lever 46 is so positioned as to hold the throwout bar 38 in 130

retracted position, as shown in Fig. 4. This leaves the slide rod 31 free to move to shift the clutch 25 into alternate engagement with the hubs of the bevel gears 22, 23. When 5 it is desired to start up the machine, the motor 18 is started which imparts a continuous rotary movement to the shaft 15 and clutch 25. If, at the start, wheel 63 is in proper position, pin 69 will enter directly 10 into one of the slots of the star wheel 63 and give it a partial rotation. If the wheel is not accurately positioned, the pin will strike the crown of one of its points which will push the wheel quickly forward or 15 backward until one of the slots comes opposite the pin and admits it. The advantage of this construction is that it prevents damage to the mechanism in case the star wheel should be out of position, either due to the 20 handling of the machine by a person unfamiliar with its principle of operation or as a result of operating the emergency lever. Ordinarily, however, the ball latch 76 will hold the star wheel in proper angular position. 25 As the drive pin rotates, it imparts a step by step movement to the star wheel and pin 64 and finally causes the pin 64 to actuate the arm 57. On account of the presence of the quick throw or full stroke 30 mechanism comprising the plunger 83 and associated parts, it is not necessary for pin 64 to move arm 57 far enough to complete the shifting of the clutch. As soon as the rock shaft 51 has been rotated slightly more 35 than half of its full angular movement, said full stroke mechanism acts and completes the movement necessary to completely shift the clutch. After the shifting movement of the clutch has been completed, said mechanism 40 will yieldingly latch the clutch in acting position. Ordinarily, the machine will be stopped by simply turning off the current from the motor, but in case of an emergency, the machine can be instantly stopped by 45 throwing the emergency lever 46. This thrusts the bar 38 toward the block 35 and shifts the clutch to neutral position and holds it there.

It will be noted that according to my design 50 the gearing is practically all located beneath the main receptacle 1, thus not only improving the appearance, but also promoting safety, for the gear parts are so protected that it would be practically impossible 55 for external objects, such as the clothing of the operator, to become caught in any part of the gearing.

In the preferred design, the wringer 90 is driven through suitable gearing from a 60 wringer shaft 94 which, in turn, is driven by suitable gearing from the shaft 15. As best shown in Figs. 1 and 2, this wringer shaft is located within the framework of the machine which thus forms a housing 65 for it.

Having thus described my invention what I claim as new and desire to secure by Letters Patent is:

1. A reversing gearing having a shiftable reversing clutch, a rotatable reversing arm 70 connected to said clutch for shifting it, a drive pin for actuating said reversing arm, said pin being adapted to travel in a circular path, means for imparting a step by step

movement to said pin along its circular path, and full stroke mechanism also connected to said clutch for completing its shifting movement, said pin making oneway engagement with said reversing arm whereby the arm may leave the pin to thereby afford free operation of the full stroke mechanism. 80

2. A reversing gearing having a shiftable reversing clutch, a pivoted reversing arm 85 connected to said clutch for shifting it, a wheel coaxial with said arm and rotatable independently thereof, means for imparting a step by step rotary movement to said wheel, a driving pin on said wheel in position to actuate said reversing arm, and full stroke mechanism also connected to said clutch for completing its shifting movement, said pin making oneway engagement with 90 said reversing arm whereby the arm may leave the pin to afford free movement to the full stroke mechanism. 95

3. A reversing gearing having a shiftable reversing clutch, a rotatable reversing arm connected to said clutch for shifting it, a drive pin for actuating said reversing arm, said pin being adapted to travel in a circular path, means for imparting a step by step movement to said pin along its circular path, full stroke mechanism also connected to said clutch for completing its shifting movement, said pin making one way engagement with 100 said reversing arm, and means for yieldingly holding said pin during the intervals between its successive movements. 105

4. Reversing gearing having a shiftable reversing clutch, a pivoted reversing arm 110 connected to said clutch for shifting it, a star wheel for actuating said arm, said wheel being coaxial with said arm and rotatable independently thereof, means for imparting a step by step rotation to said wheel, a driving pin mounted eccentrically on the star wheel for driving said arm, full stroke mechanism also connected to said clutch for completing its shifting movement, said pin making oneway engagement with 115 said reversing arm, and means for yieldingly holding said star wheel against accidental movement during its periods of rest. 120

5. Reversing gearing having a shiftable reversing clutch, an arm for shifting said clutch, a star wheel adapted to control said arm, said star wheel having radial slots in the periphery, an actuating pin traveling in a circular path, eccentric to the star wheel, for actuating it, said pin being adapted to 130

approach said wheel from the side thereof to enter the slots one after another for imparting a step by step rotary movement to the wheel, the points of said wheel being 5 crowned to thereby cause the wheel to be rotated slightly forward or backward by the pin in case no one of the slots is in position to be entered by the pin.

6. Reversing gearing having a reversible 10 bevel gear having a pin located at one side of the axis, a reversible star wheel having slots adapted to be entered by said pin to receive a step by step movement from it, a reversing arm adapted to oscillate about the 15 produced axis of the star wheel, said star wheel having a projection adapted to engage the reversing arm on two different sides alternately, a drive shaft, a clutch slidable thereon, and bevel gears in mesh with opposite 20 site sides of the first mentioned beveled gear and adapted to be engaged alternately by said clutch, said clutch being connected to and operated by said reversing arm.

7. Reversing gearing having a reversible bevel gear having a pin located at one side 25 of the axis, a reversible star wheel having slots adapted to be entered by said pin to receive a step by step movement from it, a reversing arm adapted to oscillate about the produced axis of the star wheel, said star 30 wheel having a projection adapted to engage the reversing arm on two different sides alternately, a drive shaft, a clutch slidable thereon, bevel gears in mesh with opposite 35 sides of the first mentioned beveled gear and adapted to be engaged alternately by said clutch, said clutch being connected to and operated by said reversing arm, and full stroke mechanism connected to said clutch for completing the shifting movement there- 40 of, said star wheel making oneway engagement with said arm to thereby afford freedom of action to the full stroke mechanism.

In witness whereof, I have hereunto subscribed my name.

JOSEPH KRABEC.
